DESIGN FOR A WOVEN FABRIC

John L. Walther, New York, N. Y.

Application June 16, 1937, Serial No. 69,862

Term of patent 3½ years

To all whom it may concern:

Be it known that I, John L. Walther, a citizen of the United States of America, residing in the city of New York, county of New York, and State of New York, have invented a new, original, and ornamental Design for a Woven Fabric, of which the following is a specification, reference being had to the accompanying drawing, forming part thereof.

The figure on the drawing is a plan view of a woven fabric showing my new design.

This design consists of alternate rows of wide and narrow stripes, the narrow stripes embodying loop-like elements suggestive of fur.

I claim;

The ornamental design for a woven fabric substantially as shown and described.

JOHN L. WALThER.
